UNITED STATES PATENT OFFICE.

VINCENT LINK, OF DETROIT, MICHIGAN, ASSIGNOR TO THE STUDEBAKER CORPORATION, A CORPORATION OF NEW JERSEY.

INTERNAL-COMBUSTION ENGINE.

1,393,295.

Specification of Letters Patent. Patented Oct. 11, 1921.

Application filed January 29, 1918. Serial No. 273,754.

To all whom it may concern:

Be it known that I, VINCENT LINK, a citizen of the United States, residing in the city of Detroit, county of Wayne, and State of Michigan, have invented certain new and useful Internal-Combustion Engines, of which the following is a specification.

This invention is an internal combustion engine, and, speaking generally, the salient feature of the invention consists in so constructing the engine cylinder that a certain portion thereof, preferably a part of the cylinder head, becomes heated to a considerably higher degree than other portions of the cylinder, whereby, when the explosive mixture is discharged or projected against said heated portion, it completely vaporizes, or partially gasifies, the gasoline, or other hydrocarbon fuel employed, thereby greatly facilitating its combustion, and thus increasing the efficiency of the engine.

In engines of the Diesel type, it is common practice to provide a hot-ball or vaporizing chamber, exteriorly of the cylinder, through which the fuel passes on its way to the cylinder for the purpose of assisting in the vaporization or gasification of the fuel. Manifestly, however, if such vaporization could be effected within the cylinder, it would result in a more efficient operation of the engine. Accordingly, the present invention is aimed to secure at least some of the advantages of the Diesel type of engine, and yet dispenses with the hot-ball or analogous device forming a part of the Diesel structure.

From a more specific standpoint, the invention consists in water-jacketing a portion only of the cylinder head whereby the remaining portion, not being water-cooled, becomes heated to a sufficiently high temperature to thoroughly vaporize, or gasify, the incoming gasoline or other hydrocarbon, and, thereby, greatly facilitate its combustion.

At the present time, owing to the extraordinary demand for gasoline, most of the motor fuel on the market is of a considerably lower specific gravity than that formerly employed, some of these liquid fuels containing an admixture of petroleum distillates almost as heavy as kerosene. In engines of the common type, motor fuels of this character occasion undue deposits of carbon

in the cylinder, with resulting loss of efficiency and other attendant disadvantages.

The present engine, embodying, as it does, auxiliary means for thoroughly vaporizing or gasifying the hydrocarbons, prior to their explosion, will operate with pronounced efficiency even on the heavy fuels adverted to.

Features of the invention, other than those referred to, as well as the advantages thereof, will be apparent from the following description taken in conjunction with the accompanying drawings.

The drawings illustrate the preferred, practical embodiment of the invention, but the construction shown therein is typical, only, and not exclusive of the other forms in which the invention may be availed of.

Figure 1 is, in the main, a sectional view through the middle of an engine cylinder embodying the invention, showing certain associated parts in elevation;

Fig. 2 is a plan view, assuming the cylinder to be positioned vertically, of the cylinder with the head removed.

Fig. 3 is a top perspective view of a casting forming the cylinder heads of a six cylinder engine embodying the present invention; and,

Fig. 4 is a bottom perspective view of the same casting.

Referring to the drawings, 1 designates the engine cylinder, 2 the piston, provided with piston rod 3, and 4 the water jacket at the sides of the cylinder. It will be noted that one portion 5 of the cylinder head, substantially one half of the same, is plain, *i. e.*, not provided with a water jacket, whereas the remaining portion 6 is provided with a water jacket 7 as shown. As a result of this manner of water-jacketing the cylinder head, the part 5 becomes heated to a very considerably higher temperature than the part 6, and in effect, is a hot plate. The cylinder head is preferably inclined with reference to the walls of the cylinder instead of being positioned perpendicular thereto as is customary.

The fuel inlet is shown at 8, the cylinder inlet port 9, being provided with a valve 10. The exhaust port is shown at 9', Fig. 2, and it is controlled by an exhaust valve, not shown, the same as valve 10, operating in proper timed relation to said valve 10. Both valves being of the same construction, and

operating in the same way, a description of one will suffice. The stem 11, as well as the valve, are preferably positioned at an angle to the sides of the cylinder, said stem passing through a bore in a cast portion 12, positioned laterally of the cylinder whereby the stem is properly guided. By thus placing the valve in an angular position substantially centralizes the combustion chamber 5 with reference to the cylinder bore, as a charge centralized in this way, ignites and burns more rapidly. Moreover, this inclination permits positioning of the inlet valve close to the cylinder, thereby eliminating any combustion space exteriorly of the cylinder. Said cast portion 12 is provided with a hub 13, which, in conjunction with a plate 14, secured to the lower end of stem, serves to hold a tension spring 15 in place on the stem. 10 The lift of valve 10 is effected by means of a bell crank 16, fulcrumed at 17, the bell crank being actuated by a cam 18 on cam shaft 19, over which cam rides a roller 20, carried by one arm of the bell crank. The arm of the bell crank which immediately imparts movement to valve stem 11 is preferably made longer than the arm carrying roller 20, thereby permitting of the employment 15 of a cam with a smaller lift, while giving the same lift of valve. In this manner a large valve lift can be effectively attained, and this is a decided advantage because of the increased volume of explosive mixture 20 which can be fed into the cylinder, at each operation of the valve. The present construction however, permits of increased valve lift without necessitating a corresponding increase in the size of the cam. 25 The long arm of the bell crank carries an adjusting screw 21 for accurately adjusting the throw of the valve. The valve operating parts described are readily accessible for adjustment or repair, but are protected 30 by an easily detachable plate 22. A spark plug 23 is positioned substantially centrally of the hot portion or plate 5, but the water jacket 7, being positioned close thereto, protects the plug from burning or undue heating. 35 From the foregoing description, the operation of the engine will be readily understood, but it may be briefly described as follows: The cycle is the ordinary one, namely; upon 40 the down-stroke of the piston, the explosive mixture is drawn into the cylinder, and compressed by the succeeding up-stroke, whereupon the compressed mixture is fired and forces the piston down on its working stroke; the following up-stroke scavenges the cylinder and the described operations 45 repeated. The unprotected portion 5 of the cylinder head soon becomes highly heated and the entering explosive mixture impinging as it does on the very hot cylinder 50 head, results in a complete vaporization and partial gasification of the gasoline or other hydrocarbon. Because of the angular positioning of the cylinder head and the location of the inlet, the explosive mixture on 55 entering the cylinder will strike the less heated portion of the head or plate first, and the unvaporized hydrocarbon contained in the mixture will flow down the inclined head, successively meeting hotter portions 60 thereof until it is finally vaporized. This thorough vaporization and partial gasification of the hydrocarbon, prior to the explosion of the charge, insures complete combustion under conditions conducive to high efficiency and without consequential deposits of free carbon. 65 The described operations, constituting as they do a novel method of operating gas engines, also forms part of the present invention and it is to be understood that the same is included in the averments of the annexed oath. 70 While the invention has been described, in the interest of simplicity, in connection with a single cylinder, it will be understood, of course, that it is equally applicable to multi-cylinder engines. For the purpose of illustration, however, I have shown in Figs. 3 and 4 the manner in which a six cylinder 75 cylinder head is, in practice, made to embody the present invention. The cylinder heads for all the cylinders are cast in one piece with an inclined surface 6* formed for juxtaposition with each of the cylinders. 80 This showing clearly illustrates the preferred manner of practising the invention in a multi-cylinder vertical engine, though, manifestly, the invention is not restricted to the specific details shown in Figs. 3 and 4. 85 100 It will be understood, further, that formal and mechanical changes may be made in the specific structure described, such as the use of equivalents, and that one or more of the features of the invention may be advantageously employed without utilizing them all in conjunction, without departing from the spirit or substance of the invention, the scope of which is commensurate with the appended claims. 105 110 115 What I claim as new and desire to secure by Letters Patent is:

1. In an internal combustion engine a cylinder provided with a cylinder head inclined with reference to the bore of the cylinder, a portion of said cylinder head being water jacketed, in combination with means to deliver the unvolatilized portion of the explosive fluid to the water jacketed surface of the cylinder head. 120 125
2. In an internal combustion engine a cylinder provided with a cylinder head inclined with reference to the bore of the cylinder, a portion of said cylinder head being water jacketed, in combination with means 130

to deliver the unvolatilized portion of the explosive fluid to the water jacketed surface of the cylinder head, and means independent of the hot unjacketed portion of the cylinder head for firing the explosive charge.

3. In an internal combustion engine, a cylinder provided with a cylinder head inclined with reference to the bore of the cylinder, a water jacket on a portion only of the head and an inlet port, a controlling valve therefor also inclined in relation to the bore of the cylinder, a rock-shaft for operating the valve and a cam for actuating the rock-shaft.

10 4. In an internal combustion engine, a cylinder provided with a cylinder head, a portion of which is water jacketed and a further portion of which is not water jacketed, the water jacketed portion being inclined with reference to the bore of the cylinder, a fuel inlet positioned beneath the water jacketed portion of the cylinder head, whereby the unvaporized hydrocarbon carried by the explosive mixture entering the cylinder, impinges the inclined wall of the jacketed portion of the cylinder head and flows down the inclined surface thereof onto the heated surface of the unjacketed portion of said head, said unjacketed portion being heated during the operation of the engine, but being sufficiently cooled by the jacketed portion to preclude the explosive charge from firing by contact therewith either before or during compression.

20 5. In an internal combustion engine, a cylinder provided with a cylinder head, a portion of which is water jacketed and a further portion of which is not water jacketed, the water jacketed portion being inclined with reference to the bore of the cylinder, a fuel inlet positioned beneath the water jacketed portion of the cylinder head,

whereby the unvaporized hydrocarbon carried by the explosive mixture entering the cylinder, impinges the inclined wall of the 45 jacketed portion of the cylinder head and flows down the inclined surface thereof onto the heated surface of the unjacketed portion of said head, said unjacketed portion being heated during the operation of the engine, but being sufficiently cooled by the 50 jacketed portion to preclude the explosive charge from firing by contact therewith either before or during compression, and means independent for its operation upon 55 the heated jacketed portion of the cylinder head for firing the explosive charge.

6. In an internal combustion engine, a cylinder, a fuel inlet positioned at one side of the cylinder, a cylinder head covering the 60 top of the cylinder and the fuel inlet, said cylinder head having a water jacketed portion over the fuel inlet and an unwater jacketed portion over the cylinder, which latter portion becomes heated during the operation 65 of the engine, whereby motive fuel drawn into the cylinder during the suction stroke of the piston is caused to pass from beneath the relatively cool jacketed portion of the cylinder head to and apast the heated 70 unjacketed portion thereof, the jacketed portion of said head above the fuel inlet being inclined with relation to the cylinder, so that unvaporized hydrocarbon carried by the explosive mixture entering the cylinder 75 flows down the inclined surface of the cylinder head and engages with the heated unjacketed portion thereof.

Signed by me at Detroit, Michigan, U. S. A., this 21st day of January, 1919.

VINCENT LINK.
